APPARATUS FOR CRACKING OIL

Carl E. Kleiber, Irvington, N. J., assignor to
Standard Oil Development Company, a corpora-
tion of Delaware

Application December 23, 1936, Serial No. 117,386

8 Claims. (Cl. 196—134)

This invention relates to an apparatus for use in cracking hydrocarbon oil and pertains more particularly to an apparatus for controlling the cleanliness of the intermediate condensate or cycle stock obtained during the cracking treatment, and which is normally subjected to further cracking treatment in the same or different cracking unit.

In conventional cracking processes, it is a practice to secure an initial separation of the cracked products into vapors and residue upon leaving the reaction zone and to then fractionate the vapors so separated to condense insufficiently cracked constituents as reflux condensate. This reflux condensate is then subjected to further cracking treatment in the same or different cracking unit. In order to insure a maximum amount of cracking of this reflux condensate during its passage through the reaction zone of the cracking unit, it is essential that it be relatively free of residual and coke-forming constituents, for it is generally known that the temperature to which the charge may be heated and the amount of conversion to the desired products which may be effected during the passage of the oil through the cracking unit depends upon the cleanliness of the charging stock passed thereto.

It has heretofore been a common practice to introduce a cooling oil into the top of the vapor separating zone in order to cool the cracked vapors and condense and knock back heavy coke-forming constituents and entrained residue contained therein in order to effect the desired separation of this residual coke-forming material from the cracked vapors and thus insure a clean condensate stock amenable to high temperature drastic cracking conditions.

The cooling fluid introduced into the top of the vapor separating zone as a cooling and refluxing medium therefore, may be obtained from a number of different sources. One practice is to pass the vapors from the vapor and residue separating zone through heat exchange equipment commonly referred to as reflux condensers or intercondensers positioned in the vapor line leading from the vapor separator to the fractionating equipment wherein the vapors are caused to undergo partial condensation and the condensates so formed are then returned to the vapor separating zone as a refluxing medium. According to this practice the separation of the dirty residual coke-forming constituents from the vapors is effected partly in the top of the vaporizing zone and partly in the intercondensers. In order to provide the required amount of reflux

medium under all conditions of operation and, in addition, to provide means for accurately controlling the cleanliness of the reflux condensate, the intercondensers are designed to produce more condensate than necessary for refluxing the top 5 of the vapor separator under normal operating conditions.

In such equipment where the entire condensate formed in the intercondensers is returned to the vapor separating zone for control purposes the 10 amount of condensate produced may be regulated by controlling the amount of cooling in the intercondensers. However, this method of regulating the amount of condensate returned to the vapor separating zone is of limited flexibility particularly when the cooling medium, as in most equipment arrangements, is in the preheating circuit of the cracking unit. Because of such lack of flexibility it is difficult with such an arrangement of equipment to effect a rapid and accurate control of the amount of refluxing to the 15 vaporizing zone so as to accurately regulate the cleanliness and color of the condensate in the fractionating equipment.

The usual practice in this type of cracking 20 equipment is to provide an excess of intercondenser surface and to combine the excess condensate over and above that required to effect the desired refluxing in the vapor separating zone with the cycle condensate formed in the fractionating equipment and to subject it to further 25 cracking treatment therewith. Since, as already pointed out, the separation of heavy residual and coke-forming constituents from the vapors is usually completed in the intercondensers, there 30 being difficulty in securing the desired separation in the vaporizing zone, it will be apparent that if aliquot portions of the total condensate from the intercondensers are returned to the vapor separator and the remaining condensate 35 combined with the cycle stock from the fractionating equipment, the remaining condensate will be contaminated with dirty constituents 40 which will degrade the cycle stock.

To avoid this, insofar as possible, it has been a 45 practice in some cases to separately withdraw condensate formed in the separate passes of the intercondensers and return the dirtier condensate from the first passes to the vapor separator and combine the relatively cleaner condensate 50 from the final passes of the intercondensers with the cycle stock formed in the fractionating equipment for further cracking.

In some instances, for example, a fixed amount 55 of condensate from the initial passes of the

- intercondensers, sufficient to meet the minimum reflux requirements for the vapor separator is returned thereto and any additional condensate necessary to effect the desired cooling in the top 5 of the vapor separating zone is obtained by returning an aliquot portion of the condensate from the final passes of the intercondensers. While this mode of operation offers some advantages over returning aliquot portions of the total condensate, it is open to the objection that the aliquot portion of the condensate returned to the vapor separating zone as a reflux medium is of the same composition as that combined with the reflux condensate from the fractionating equipment, whereas under the most ideal conditions the cleanest condensate fraction would always be combined with the cycle condensate to be further cracked and the dirtiest fraction returned to the vapor separating zone as reflux control.
- 10 It has also been a practice in some instances, to provide sufficient valves and manifolding so that any one or more of the several condensates withdrawn from the separate passes of the intercondenser can be selectively passed either to the vapor separating zone or combined with the reflux condensate from the fractionating equipment. While this makes it possible to combine the cleanest condensate with the reflux condensate formed in the fractionating equipment and 15 return the dirtiest fraction to the vapor separating zone, it is open to the objection that it increases the burden on the operator to properly regulate the numerous manifold valves required, and it also materially increases the cost of equipment due to the relatively high cost of the regulating valves and manifolding so required.
- 20 One of the objects of my invention is to overcome the objections of the apparatus heretofore employed and provide a more simple and improved apparatus which will separate, collect and selectively distribute the separate condensate fractions removed from the separate passes of the intercondenser so that under all conditions of operation only the cleanest fraction will be combined with the reflux condensate formed in the fractionating equipment.
- 25 Another object of my invention is to provide a more simple and improved apparatus which may be operated by a single control so as to selectively distribute the condensate from the intercondensers to cause the dirtiest condensate to be returned to the vapor separating zone and the cleanest to the fractionating equipment.
- 30 A more specific object of my invention is to provide a simple gravity runback system for collecting and distributing condensate from the intercondensers which may be operated by a single control to cause any desired amount of the total condensate to be returned either to the vapor separating zone or combined with cycle stock and which under all conditions of operation will cause only the dirtiest condensate to pass to the vapor separating zone.
- 35 Other and more specific objects of my invention will be apparent from the more detailed description hereinafter, in which reference will be made to the accompanying drawings.

In the drawings:

- 40 Fig. 1 is a diagrammatic flow diagram of a simple oil cracking unit having my improved intercondenser and runback system connected therewith;

45 Fig. 2 is an enlarged detailed sectional view 75 showing the construction of the intercondensers;

Fig. 3 is an enlarged detailed view of the intercondensers and runback system; and

Fig. 4 is an enlarged detailed view of another modification of my improved intercondensers and runback system.

50 Referring to Fig. 1, the line 10 designates a charging line through which the oil to be cracked is introduced to the system. The line 10 is provided with a pump 11 which forces the oil to the second or cooler of two intercondensers 12 and 13, located in the vapor line 14, connecting the vapor and residue separating zone 15 with the fractionating tower 16.

55 As shown in Fig. 2, the fresh charging oil passes into a lower header 17 separated from the main body of the intercondenser 13 by means of a partition 18. The lower header 17 communicates with an upper header 19 by means of a plurality of banks of tubes 20. The lower header 17 is divided into a plurality of vertical compartments by means of partition walls 21 and 22, and the upper header is divided into a plurality of staggered compartments by means of partition wall 23, so that the fresh charging oil is caused to pass alternately upwardly and downwardly through the intercondenser in indirect countercurrent heat exchange relation with the cracked vapors passing therethrough as herein-after described.

60 The fresh charging oil after passing through the second intercondenser 13 passes through the first intercondenser 12 wherein it passes in further heat exchange relation with the vapors from the vapor separating zone 15. The intercondenser 12 is of the same construction as the intercondenser 13.

65 The fresh oil or cooling medium after passing through the first of the two intercondensers emerges therefrom through line 24 which connects with a heating coil 25 located within the furnace 26. A by-pass line 24' may be provided around the intercondensers to regulate the amount cooling within the intercondensers and provide an additional range of flexibility permitted by the required heat-pickup by the cooling medium.

70 The oil during its passage through the heating coil 25 is heated to a cracking temperature and maintained at cracking temperature for a period sufficient to effect the desired cracking thereof. The cracked products from the heating coil 25 then pass through line 27 to the vapor separating zone 15, wherein the vapors separate from the residue or fractions no longer suitable for further passage thru the immediate cracking zone. Residue separated in the vapor separating zone 15 is withdrawn therefrom through line 28 and passed to storage receptacles (not shown) or subjected to any desired further treatment.

75 The upper end of the vapor separating chamber 15 may be provided with suitable baffles, such as disc and doughnut baffles to aid in knocking back residual constituents entrained in the vapors. Vapors separated in the vapor separating chamber 15 pass overhead through line 14 to the main body of the first intercondenser 12.

80 As shown in Fig. 2, the main body of the intercondenser is usually provided with one or more vertical baffle plates 29, separating the intercondenser into a plurality of cooling zones through which the vapors pass alternately upward and downward in indirect countercurrent contact with the tubes 20 containing the fresh oil as a cooling medium.

85 The vapors during their passage through their

several passes of the intercondenser are subjected to progressive cooling by the fresh oil and the higher boiling constituents thereof are condensed and separated from the vapors by collecting in the bottom of the main section of the intercondenser.

The separate passes of the intercondenser are provided with separate outlet ports and separate downwardly extending outlet pipes or legs 35, 36, 10 37 and 38 which connect with a common manifold line 39 so that condensate formed in each pass is separately withdrawn from the intercondenser and passes into the common manifold 39. It will be understood that the first condensate 15 formed in the initial pass of the intercondenser will be the heaviest and dirtiest condensate and containing a maximum of coke forming residues while the condensate formed in the succeeding passes will be progressively lighter and cleaner.

20 The vapors after passing through the first intercondenser 12 and undergoing partial condensation therein continue through vapor line 14 to the second intercondenser 13, wherein they are subjected to further partial condensation. As 25 already described, the second intercondenser 13 is of the same construction as the first intercondenser. The condensates formed in the separate passes of the second intercondenser 13 are withdrawn through lines 41, 42, 43 and 44, which also 30 connect with the main manifold line 39.

Vapors remaining uncondensed after passing through the second intercondenser 13 continue 35 through line 14 to the fractionating tower 16 wherein they are subjected to fractionation to condense insufficiently cracked constituents as reflux condensate. Vapors remaining uncondensed in the fractionating tower 16 pass overhead through line 45 to a condenser 46 wherein the desired distillate is condensed. Products from 40 the condenser 46 then pass to a distillate receiver 47, wherein fixed gases separate from the distillate. The desired distillate product is withdrawn from the receiver 47 through line 48 and the fixed gases pass overhead through line 49 45 provided with a valve 50 for maintaining the desired pressure on the system. As a means of controlling the fractionation operation performed in tower 16 a part of the cooled distillate withdrawn from receiver 47 may be returned to the top of 50 tower 16.

Reflux condensate formed in the fractionating tower 16 is withdrawn from the bottom thereof through line 51 and is forced by means of pump 52 to the inlet side of the heating coil 25 where 55 it combines with fresh makeup oil for the process. While I have shown the recycling of the reflux condensate to the original cracking coil, it will be understood that in many types of operations this reflux condensate is subjected to separate cracking treatment under optimum conditions for converting or cracking this type of stock.

As already pointed out in the objects of my invention, I provide a simple gravity runback system for the condensate formed in the intercondensers, which makes possible the separation of the total condensate into a relatively clean fraction and a relatively dirty fraction by the operation of a single control valve. In practical operations, the relatively clean fraction is combined with the cycle stock formed by condensing insufficiently cracked constituents of the vapors. To this end, the clean fraction may be introduced directly into the fractionating tower 16 or it may be combined with the cycle stock formed therein, 70 in a separate storage receptacle, not shown. 75

Likewise, in practical operations, the dirtiest fraction of the intercondenser condensate is returned to the top of the vapor separator as a reflux medium therefor, although this stock may be withdrawn from the system and utilized in other manners, and a separate reflux medium introduced into the top of the vapor separator.

Referring particularly to the modification shown in Figs. 1 and 3, the manifold 39 receiving condensate from the intercondensers connects at 10 the end nearest the second intercondenser with a line 53, provided with a throttle valve 54. Line 53 connects with the fractionating tower 16 through line 55, so as to discharge condensate from line 53 directly into the fractionating tower. 15 A branch line 56 is also shown for withdrawing any desired part or all the condensate from line 53 from the system.

The opposite end of the manifold 39 nearest the vapor separator 15 connects with an upwardly extending inverted U-shaped pipe line 57, having the apex communicating with a vent line 58. Vent line 58 connects with the vapor line 14 beyond the second intercondenser 13.

The vertical height of the inverted U-shaped 25 pipe line 57 determines the level of liquid maintained in the runback system. This height should be sufficient to maintain the manifold 39 completely filled with liquid throughout the full length thereof, but should not be high enough 30 to cause condensate from the final pass of the intercondenser 13 to overflow into the vapor outlet line 14. As a matter of practice, it is preferred to terminate the upwardly extending U-shaped section 57 below the condensate outlet 35 ports from the intercondensers so as to maintain the liquid level within the legs 43 and 44, connecting the manifold 39 with the final passes of the second intercondenser 13, rather than in the main shell of the latter intercondenser. 40

The level of liquid condensate in the individual legs 35, 36, 37 and 38 for the first intercondenser 12, and 41, 42, 43 and 44 for the second intercondenser 13, will depend upon the vapor pressure above the liquid in the respective legs 45 and the level of liquid in the individual legs will be progressively higher from left to right as shown in Figs. 2 and 3, due to the drop in pressure of the vapors during their passage through the intercondensers. These legs should be of 50 sufficient length therefore to insure a liquid seal at the point of junction of the first leg 35 with the manifold 39, in order to prevent vapors from entering the manifold 39 by-passing the various passes of the intercondensers and inducing an 55 unsatisfactory operation of the equipment. In this connection, it is worthy of note that it is of extreme importance to my invention to maintain the manifold line 39 completely filled with liquid, for the presence of vapors therein causes agitation of the condensate from the various legs and the surging of the condensate back and forth through the manifold and making it impossible to effect a sharp separation of condensates from the separate condensate legs. 60

The line 53 communicating with the manifold 39 at the end adjacent the second intercondenser 13 is provided with a vent line 59 which also communicates with the vapor line 14 beyond the second intercondenser. As a matter of practice, 70 it is usually found desirable to merge the vent line 58 and the vent line 59 to the same point in the vapor line 14, so that both ends of the manifold 39 will be under substantially the same back pressure, except for the difference in pres- 75

- sure drop through the vent lines themselves. The vent lines 58 and 59 permit vapors formed by commingling relatively colder condensate formed in the later vapor passes of intercondensers with the relatively hotter condensate formed in the earlier passes of the intercondensers to rapidly separate from the two streams of the combined condensate at both ends of manifold 39. It has been found, for example, that unless vent lines of this character are provided of sufficient size to rapidly remove the vapors formed in the manifold 39, there will be a constant surging of condensate in the manifold with a corresponding change in the level of condensate in the vertical legs 35, 36, 37, 38 and 41, 42, 43 and 44. This change in level will in turn change the pressure on the liquid passing through the control valve 54 and the surging of the condensate back and forth longitudinally in the manifold of 39 will cause contamination of condensate formed in the final passes of the intercondensers with condensate formed in the initial passes and thus destroy one of the important objects of my invention.
- 25 The upwardly extending inverted U-shaped pipe section 57 connecting with the manifold line 39 connects with a downwardly extending U-shaped section 68 which terminates within the vapor separator 15 at a point substantially below the condensate liquid levels in the runback legs 35, 36, 37, 38, etc. A separate withdrawal line 61 is provided whereby a part or all of the condensate flowing to the vapor separator may be diverted from the process.
- 30 By the construction described above, it is possible, in accordance with my invention, to maintain a constant level of liquid in the runback system extending from the apex of the inverted U-shaped section 57 to the throttle valve 54 so that for any given setting of the valve 54 a uniform flow of condensate therethrough will be attained, while the surplus condensate will be automatically diverted in the opposite direction. As already pointed out, by providing means to insure that manifold line 39 is completely filled with liquid, by preventing any portion of the vapors from the intercondenser passing into the manifold and by effecting a rapid separation of vapors formed in the manifold, surging and agitation of the condensate within the manifold is avoided so that any desired portion of the relatively dirtiest condensate from the earlier passes of the intercondensers will be caused to flow toward the vapor separator and the remaining relatively cleaner condensate caused to flow toward the fractionating tower.
- 35 For example, if it is determined by inspection of condensate samples from the various legs of the intercondensers that only the condensate collected in the last two legs 43 and 44 is sufficiently clean for use as cracking stock, the throttle valve 54 will be set to withdraw condensate at the same rate it collects in these two legs. That portion of the manifold between legs 42 and 43 will then become a zone of quiescence and the condensate collected in the first six legs of the intercondensers will pass toward the vapor separator and the condensate formed in the last two legs will flow toward the fractionating tower.
- 40 The modification shown in Figs. 1 and 3, wherein the control valve is located in the line connecting the manifold 39 with the fractionating tower 16, finds particular advantage in processes where it is desired to accurately control the cleanliness of the condensate subjected

to re-cracking. In other processes, it is often desirable to regulate the amount of reflux medium introduced into the vapor separator so that the tar withdrawn as residue through line 28 is of a desired quality in such respects as gravity, etc. 5 Figure 4 shows a modification of my invention wherein the amount of reflux return to the separator 15 is subjected to primary control and the surplus condensate formed in the final passes of the intercondensers is diverted to the fractionating tower 16. According to this modification the line 53 leading from the manifold 39 to the fractionating tower 16 is provided with an inverted U-shaped section 62 similar to that shown in line 57 of Fig. 1 which serves to maintain the 10 manifold 39 completely filled with liquid. As shown the line connecting the manifold with the separator is provided with a variable speed pump 63 which serves as a control for regulating the amount of reflux required for the separator. The 15 excess condensate passes in the opposite direction through line 53 to the fractionating tower 16 or out of the system through line 56. In lieu of the variable speed pump 63 a simple throttle valve 54 such as that located in line 53 in Fig. 1 may 20 be employed. The control valve is preferred rather than the variable speed pump and the latter is used only when previous designs do not provide sufficient gravity head to permit return of condensate to the separator. 25

In other respects the apparatus is the same as that shown in Figures 1 to 3.

While I have shown two separate intercondensers 12 and 13, it will be understood that my invention is not limited thereto. A single intercondenser of desired capacity or three or more intercondensers may be substituted therefor. Also in lieu of using fresh charging stock as a cooling medium in the intercondensers, other cooling mediums may be employed. Moreover, 35 the cooling medium may be passed in parallel through the separate intercondensers rather than in series. However, to obtain the greatest benefits from my invention the vapor passing through the intercondensers should contact with 40 progressively cooler heat exchange surface so that the condensates withdrawn from the successive legs will be of progressively increasing cleanliness. 45

Having described the preferred embodiment, 50 it is understood that my invention is not limited thereto but includes such other variations and modifications as come within the spirit and scope thereof.

I claim:

1. In an oil cracking apparatus, means for separating the cracked products into vapors and residue, a vapor line, intercondenser means disposed in said vapor line for fractionally condensing the cracked vapors into a plurality of condensate fractions of different boiling range, a fractionating column means for separately removing said condensate fractions from said fractionating means, a common manifold conduit means for introducing said condensate fractions so removed into the common manifold conduit at spaced points longitudinally thereof in the order of the relative boiling range of said fractions, whereby the lowest boiling condensate is introduced into said manifold conduit adjacent one end thereof and the highest boiling condensate fraction is introduced into said manifold conduit adjacent the opposite end thereof, a vent pipe in communication at one end thereof with the manifold at the end thereof where the highest 75

boiling fractions are received and at the other end with the vapor line and a second vent pipe in communication at one end thereof with the manifold conduit at the end where the lowest boiling fractions are received and at the other end with the vapor line, for maintaining the condensate in said manifold conduit under substantially uniform pressure, means for withdrawing condensate from each end of said manifold conduit and means operated by a single control for regulating the relative amount of condensate withdrawn from each end of said manifold.

2. In an oil cracking apparatus a vapor separator for separating the cracked products into vapors and residue, a fractionating column for fractionally condensing insufficiently cracked constituents of said vapors, a vapor conduit connecting said vapor separator with said fractionating column, an intercondenser positioned in said vapor conduit for condensing higher boiling constituents of said vapors, means dividing the intercondenser into a plurality of separate cooling zones of progressively lower temperature, means for separately removing condensate formed in each of said cooling zones, a common manifold, means for introducing the condensate withdrawn from each of said cooling zones into the common manifold conduit at spaced points longitudinally thereof in the order of the relative boiling range of said condensates, whereby the lower boiling condensate is introduced into said manifold conduit at one end thereof and the highest boiling condensate is introduced at the opposite end thereof, outlet pipes connected at each end of said manifold conduit for withdrawing condensate therefrom, a control valve in only one of said outlet pipes, a vent pipe in communication at one end thereof with the manifold at the end thereof where the highest boiling fractions are received and at the other end with the vapor line and a second vent pipe in communication at one end thereof with the manifold conduit at the end where the lowest boiling fractions are received and at the other end with the vapor line, for maintaining the condensate within said manifold to substantially uniform pressure, whereby condensate is caused to discharge through said control valve at a uniform rate for each setting thereof and surplus condensate is caused to discharge to the other of said outlet pipes.

3. In an oil cracking apparatus, a vapor separator adapted to separate the cracked products into vapors and residue, a fractionating column, a vapor conduit connecting said vapor separator with said fractionating column, an intercondenser positioned in said vapor line adapted to condense higher boiling constituents from said vapors, means for separating said intercondenser into a plurality of cooling zones, whereby the vapors passing therethrough are subjected to progressive cooling action to form a plurality of condensate fractions, means for separately removing said separate condensate fractions from said cooling zones, a manifold conduit, means for introducing the condensate fractions into said manifold conduit at spaced points longitudinally thereof in the order of the relative boiling points of said condensates, whereby the lowest boiling condensate fraction is introduced into said manifold adjacent one end thereof and progressively higher boiling constituents are introduced into said manifold conduit at successive points longitudinally thereof, an outlet pipe connected to each end of said manifold conduit, a control valve in one of said outlet pipes, vent pipes in communication with opposite ends of the manifold conduit and the vapor conduit positioned in the other of said outlet pipes for maintaining a constant pressure on the condensate in said manifold conduit, whereby for any given setting of the control valve condensate will be discharged therethrough at a uniform rate, and means for automatically discharging any surplus condensate formed in said intercondenser through the other of said outlet pipes.

4. An oil cracking apparatus, with a vapor separator adapted to separate the cracked products into vapors and residue, a fractionating column for condensing insufficiently cracked vapors, a vapor conduit connecting said vapor separator with said fractionating column, an intercondenser positioned in said vapor conduit adapted to progressively cool said vapors over an extended temperature range, means dividing said intercondenser into a plurality of cooling zones adapted to condense fractions of different boiling range, outlet pipes communicating with each of said cooling zones for separately removing condensate formed therein, a common manifold conduit connecting each of said outlet pipes for receiving condensate from each of said cooling zones, means for introducing the condensate into said common manifold at spaced points longitudinally thereof in the order of the boiling range of said condensate, outlet pipes at each end of said manifold conduit for removing condensate therefrom and control valve in one of said outlet pipes, whereby for any given setting of said control valve condensate is discharged therethrough at a uniform rate and any surplus condensate formed in said intercondenser is discharged through the other of said outlet pipes and means comprising vent pipes in communication with opposite ends of the manifold conduit and the vapor conduit at a point between the intercondenser and the fractionating column for removing vapors formed in said manifold conduit by commingling of hotter and colder condensate fractions to prevent agitation of said condensate within said manifold whereby the condensate withdrawn from one end of said manifold has a higher boiling range than the condensate withdrawn from the opposite end of said manifold.

5. In an oil cracking apparatus, a vapor separator adapted to separate the cracked products into vapors and residue, a fractionating column adapted to fractionally condense insufficiently cracked constituents of said cracked vapors, a vapor line connecting said vapor separator with said fractionating column, an intercondenser positioned in said vapor line adapted to progressively cool said vapors over an extended range, means separating said intercondenser into a plurality of cooling zones of progressively lower temperature, downwardly extending outlet pipes connected to each of said cooling zones adapted to withdraw condensate formed therein, a horizontal manifold conduit connecting each of said downwardly extending outlet pipes for receiving condensate from each of said cooling zones at spaced points longitudinally of said conduit in the order of the boiling range of said condensate fractions, an outlet pipe at each end of said horizontal manifold conduit for withdrawing condensate therefrom, a control valve in one end of said outlet pipes, an upwardly extending inverted U-shaped section communicating with the

other of said outlet pipes adapted to maintain a liquid seal and provide a constant level of liquid in said manifold and downwardly extending outlet pipes, a vent pipe connecting the U-shaped section with the vapor line and a second vent pipe connecting the end of the manifold conduit which is in communication with the outlet pipe carrying the control valve and the vapor line for removing vapors formed in said manifold conduit by commingling of separate condensates introduced therein and to prevent agitation of condensate within said manifold conduit.

6. In an oil cracking apparatus, a vapor separator for separating the cracked products into vapors and residue, a fractionating column adapted to fractionally condense insufficiently cracked constituents as reflux condensate, a vapor conduit connecting said vapor separator with said fractionating column, an intercondenser positioned in said vapor conduit adapted to progressively cool said vapors over an extended temperature range, means for dividing said intercondenser into a plurality of cooling zones of progressively lower temperature, a downwardly extending outlet pipe communicating with each of said cooling zones for separately removing condensate formed therein, a horizontal manifold conduit connecting each of said downwardly extending pipes for receiving the separate condensate fractions formed in said separate cooling zones at spaced points longitudinally of said manifold conduit in the order of the boiling range of said condensates, whereby the lowest boiling condensate is introduced into said manifold at one end thereof and progressively higher boiling condensate fractions are introduced into said manifold at successive points longitudinally thereof, a tubular conduit connecting the end of said manifold receiving the highest boiling condensate with said vapor separator, a tubular conduit communicating with the opposite end of said manifold for withdrawing lower boiling condensate, an upwardly extending inverted U-shaped section in one of said tubular conduits communicating with the ends of said manifold of a height sufficient to maintain a constant level of liquid in said manifold and downwardly extending outlet pipes, vent pipes at each end of said manifold connected to the said vapor conduit for removing vapors formed therein by the commingling of different condensates introduced into said manifold, and a control valve positioned in the tubular conduit communicating with said manifold at the end opposite the one having the inverted U-shaped section.

7. In an oil cracking apparatus a vapor separator adapted to separate the cracked products into vapors and residue, a fractionating column for fractionally condensing insufficiently cracked constituents, a vapor conduit connecting said vapor separator with said fractionating column, an intercondenser positioned in said vapor conduit adapted to progressively cool said vapors over an extended range, a plurality of vertical baffles positioned in said intercondenser dividing the same into a plurality of cooling zones, means causing said vapors to pass around said baffles in an alternate upward and downward direction,

downwardly extending outlet pipes communicating with the bottom of each of said cooling zones to separately remove condensate formed therein of progressively lower boiling range, a common manifold connecting said downwardly extending outlet pipes to receive separate condensate removed from said cooling zones, a tubular conduit connecting the end of said manifold conduit receiving the highest boiling condensate with the vapor separator, an upwardly extending inverted U-shaped section formed in said last-named conduit to provide a liquid seal of sufficient height to maintain said manifold completely filled with condensate throughout the full length thereof, a vent line connecting the upper end of said inverted U-shaped section with the vapor conduit beyond said intercondenser, an outlet conduit communicating with the other end of said manifold receiving the lowest boiling condensate fraction, a vent line connecting said last-named outlet conduit with the vapor conduit beyond said intercondenser and a control valve positioned in said last-named outlet conduit whereby regulated amounts of lower boiling condensate are withdrawn therefrom and the remaining condensate formed in said intercondenser is passed to said vapor separator.

8. In an oil cracking apparatus, a vapor separator adapted to separate the cracked products into vapors and residue, a fractionating column adapted to condense insufficiently cracked constituents, a vapor conduit connecting said vapor separator with said fractionating column, an intercondenser positioned in said vapor conduit adapted to progressively cool said vapors over an extended temperature range, a plurality of baffles positioned in said intercondenser to cause said vapors to pass therethrough in an alternate upward and downward direction through a plurality of cooling zones of progressively lower temperature, downwardly extending outlet pipes communicating with the bottom of each of said cooling zones for separately removing condensate fractions of progressively lower boiling range from said cooling zones, a manifold conduit communicating with said downwardly extending pipes to receive the condensate discharged therethrough, said condensate fractions being introduced into said manifold at successive points in the order of their boiling ranges, a tubular conduit connecting the end of said manifold receiving the highest boiling condensate with the vapor separator to return condensate formed in said intercondenser to said vapor separator as a reflux medium therefor, control means positioned in said conduit for regulating the amount of condensate returned to said vapor separator, an outlet conduit connected to the opposite end of said manifold receiving the lowest boiling condensate from said intercondenser, means in said last-named outlet conduit for maintaining a constant level of liquid in said manifold and said downwardly extending outlet pipes and vent lines positioned at the ends of said manifold and connected to the vapor line for removing vapors formed in said manifold by the commingling of separate condensates introduced therein.

CARL E. KLEIBER.
